UNITED STATES PATENT OFFICE.

THOMAS H. SYMINGTON, OF BALTIMORE, MARYLAND.

SPRING-BOX.

1,103,632.

Specification of Letters Patent. Patented July 14, 1914.

Application filed January 2, 1913. Serial No. 739,781.

To all whom it may concern:

Be it known that I, THOMAS H. SYMINGTON, a citizen of the United States of America, residing at the city of Baltimore, 5 State of Maryland, have invented certain new and useful Improvements in Spring-Boxes, of which the following is a specification.

This invention relates to a draft gear in 10 which the shock-absorbing member consists of a set of plate springs or a series of sets of such springs so placed that the buffing and drawing stresses are distributed through the plates, setting up a bending stress in 15 each plate, thus affording a yielding resistance which absorbs the shocks of buffing and drawing.

It also relates to the springs and to the 20 casing or box for inclosing and supporting the same.

Draft gears embodying the features thus described are in use. These are also the subject of various United States patents, and the present invention relates to an im- 25 proved form of the device and to various combinations of the features thereof.

In order to simplify the operation of assembling draft gears of this type, housings or boxes have been provided which serve to 30 inclose and support the plate springs. These boxes are open to a greater or less degree at the ends, and thus provision is made for the admission of followers or other means for applying the stresses of buffing 35 and drawing directly to the centers of the end plates. In the draft gears of this type heretofore in use, the spring box is an elongated tube or housing of square or rectangular cross-section, open at one end to admit 40 the springs and the various spacing members which serve to space the springs and transmit the stresses, while the other end is sufficiently closed to support the ends of the springs and open centrally to admit the fol- 45 lower or other means for applying stresses to the centers of the springs as heretofore described.

The spring boxes or housings now in use and to which reference has been made, constructed as described, are bulky and cumbersome, and with them the spring plates are necessarily placed with their greatest dimension or length horizontal. Therefore the yoke which incloses the box is in a vertical plane with its opening horizontal, the

bulk and construction of the box being such that it cannot be inserted in the horizontal yoke now most frequently used with the spiral spring and friction draft gear.

The object of the present invention is to produce a box for the spring plates, adapted to support the spring plates in a vertical position within the yoke and so constructed that it may be inclosed within the horizontal yoke which is now used with the spiral 65 spring or friction shock-absorbing member, the present device being interchangeable with the other shock-absorbing members. When they are placed vertically, the plates may be made of any convenient length and 70 are not necessarily limited in length by the distance between the sills as when placed horizontally.

Another object is to so construct the box 75 that the springs may be conveniently placed therein and the box closed and fastened so that the springs and the spacing members are secure against loss or displacement from any cause. To this end the box is made in two sections, divided on a plane transverse 80 to the length of the box. The sections of the box may be connected together in any suitable manner. In the present instance they are shown as having ears or flanges on the contacting edges or ends which are bolted 85 together. The contacting ends of the sections are open to admit the spring plates and spacers, and each end of the box is provided with means for supporting the ends of the springs, but the ends are open centrally to permit the front and rear followers 90 to bear on the front and rear plates respectively. The bearing surfaces of the followers are curved in a vertical plane centrally of their vertical length, and the front 95 and rear followers bear on the front and rear plates respectively, the contact extending across the plates substantially in a horizontal line.

Another object is to so construct the box 100 that not only the springs and spacing members may be placed therein and fastened, but that it also contains the front and rear followers, the box containing the springs, the front and rear followers and the spacing 105 members being adapted to be mounted between the front and rear stops and being suitably apertured at the front and rear so that the yoke may transmit drawing stresses directly to the rear follower while the draw- 110

bar transmits buffing stresses directly to the front follower. With the spring box described all the smaller moving parts are combined so that they are in effect a single member and may be handled as such, and the draft gear consists of but three movable and removable parts, the draw-bar, the yoke, and the box containing the springs, followers and spacing members. Thus the possibility of dropping the followers, the plates or the spacers is entirely eliminated and the operation of assembling the draft gear becomes one of extreme simplicity.

In the accompanying drawing I have illustrated a draft gear with a horizontal yoke and provided with a shock-absorbing member consisting of a set of draft plates constructed and mounted in accordance with my invention in its preferred form.

Figure 1 is a view of the draft gear divided on its center line, one half being a top plan, the other a horizontal, central section on the line 1, 1 of Fig. 2. Fig. 2 is a vertical, central, longitudinal section. Fig. 3 is a transverse vertical section taken on the broken line 3, 3 of Fig. 1. Fig. 4 is a view half in plan and half in horizontal, central cross-section showing another form of the invention.

Referring to the drawing by reference numerals, the draft gear consists of a draw-bar 1, slotted at 6 to receive a key, a horizontal yoke 2 having two sets of elongated, alined slots 3 and 4. The draft sills are provided with front and rear elongated, alined slots 7 and 8, the slots 7, as shown, exceeding in length the slots 8. A key 5 engages the forward slots 7 of the sills and extends through the forward slots 3 of the yoke, and the slot 6 of the draw-bar, fitting the latter slot.

Within the yoke is a front follower 9 slotted at 10 to fit the rear key 11, which latter key engages the rear slots 8 in the sills and extends through the rear slots 4 in the yoke.

As shown, there is a rear follower 12 within the yoke and engaged by its rear arm 13. At the rear the yoke strikes in buffing against the rear stop 14, which, as shown, is a transverse member extending from sill 50 to sill, the buffing stress applied to the rear follower being in this instance transmitted through the rear arm of the yoke in the form of a compression stress to the rear stop. It will be noted that the rear surface 55 of the front follower 9 and the front surface 16 of the rear follower 12 are curved, being convex in a vertical plane, preferably having their lateral elements straight.

Within the yoke, between the followers, the front plate 18 bearing centrally of its length against the curved surface 15 of the front follower and the rear plate 19 bearing against the curved surface 16 of the rear follower, is the shock-absorbing member 17 consisting of a plurality of sets of flat spring

plates 20. In the present instance, as illustrated, there are nine plates in each set and four sets of plates are shown but any number may be used depending upon the resistance which it is desired to oppose to the drawing and buffing shocks. In order to flex the plates and to utilize their resistance to bending in absorbing the shocks, the top and bottom ends of the front set 21 and the rear set 22 are separated from the corresponding top and bottom ends of the adjacent sets of plates 23 and 24 by means of spacing members 25 of cross-sections tapering inward toward the center of the box, and the intermediate sets 23 and 24 are spaced and supported by means of a spacing member 26, having its greatest width at its central point and tapering uniformly to its upper and lower ends.

The theory of the operation of the spring plates is apparent. The stress in buffing and drawing is applied by either follower to the center of the adjacent outside set of plates, by these plates at their ends to the spacing member 25, by this spacing member to the ends of the next intermediate set of plates 23 or 24, and by this set to the central spacer 26 which transmits the pressure to the center of the next intermediate set of plates 23 or 24, hence to the spacers 25 and to the end set of plates, which latter set of plates bears against the corresponding follower, the contact being substantially in a transverse, horizontal line as described. The follower which receives the stress from the springs is rigidly supported against the front stop or rear key 11 if drawing or against the rear stop 14 if buffing, and the stresses are thus applied to the sills, the shock being absorbed by the plates.

The spring plates described are inclosed within a box or housing, the object of which is to support the plates and simplify the operation of assembling the draft gears. The box 27, as shown, is of a cross-section similar to the plane of the plates but of slightly increased dimensions. It has openings 28 at its ends to permit the followers to engage the end plates, but the ends of the box are provided with flanges or supports 29 which take over the edges of the plates holding the various sets and the spacing members in the relative positions in which they are shown.

The box 27 is preferably divided on a central, vertical, transverse plane, so that it is actually formed in two sections 30 and 31, which meet at the longitudinal center of the box. Each section is provided with ears or flanges 32 near the contacting edges, and when the gear is set up, these sections are bolted together, as shown, and in assembling the springs, two sets, with a spacer 25, are placed in each section 30 and 31. The sections are then brought together with the central spacer 26 between the intermediate sets 130

23 and 24, and the sections are joined by bolting the ears 32 together. Each lateral face of the box is provided with parallel, horizontal flanges 34 forming a seat or pocket to receive the arms of the yoke 2. 5 To support the springs and box, any suitable bottom plate 33 is utilized, and a cover plate 34, extending from sill to sill as does the bottom plate 33, may be placed on top of the box. 10

10 The parts enumerated, combined as described, will be found to constitute an efficient plate spring shock-absorbing member which may be used with a draft gear having a 15 horizontal yoke and may be conveniently substituted therein for the usual helical spring or friction shock-absorbing member. The operation of the device will be clearly understood from the preamble and the description taken in connection with the drawings. 20

20 In Fig. 4 I have shown another embodiment of my invention. In this instance the spring box 35 is slightly elongated so that it contains not only the springs 20 and spacing members 25 and 26, but the front and rear followers 36 and 37 are also mounted within the box. The latter is preferably divided centrally on the transverse plane at 38 into two parts 39 and 40, each part being provided with ears 41 through which are passed bolts 42 for holding the two parts of the box in the relative positions shown. The box 35 and the front and rear stops 43 and 44 are so related that the box is just equal in its overall length to the distance between the stops, and the front and rear faces 45 and 46 of the box rest against the rear faces of the front stops 43 and the front faces of the rear stops 44, the stops being held in fixed relation to the frame by any suitable means. The box is shown in connection with the vertical yoke 47, but it will be apparent that the box may be turned through an angle 35 40 45 of 90° and used with a horizontal yoke as is the box first described as shown in Figs. 1, 2 and 3.

50 To permit the yoke to come in contact with the rear follower, the box is slotted or apertured at the rear end at 48, the aperture extending across the rear of the yoke and forward in the top and bottom walls as indicated. The front end of the box is similarly slotted at 49, and though the ends 55 of the box have been termed front and rear, it will be apparent that these terms are merely used for convenience and that the box is in fact easily interchangeable as to its front and rear top and bottom, etc., being symmetrical in regard to the plane 38. The apertures 48 and 49 referred to are of less dimension than the front and rear elevation of the followers 36 and 37, that is, there is a considerable portion of the end 60 65 wall of the box left at each side as at 53, 54

to support the followers and prevent their escape from the box. These portions of the box marked 53, 54 also serve to transmit, by compression to the stops 46, the buffing and drawing stresses which are applied to the 70 draft gear.

75 The operation of this device is believed to be quite apparent from the description and drawings. The box containing the springs, spacers and followers is placed between the sills resting on any suitable support as the bar 50, and engaging with its front and rear surfaces the front and rear stops 43 and 44. The yoke encircles the box bearing on the rear follower, and the rear 80 end 51 of the draw-bar 52 preferably bears on the front follower where it is exposed by the forward aperture 49. The buffing stresses are transmitted in the usual manner through the followers and springs constituting the shock-absorbing member within the box through the rear wall of the box to the rear stops, and the drawing stresses are transmitted through the yoke to the rear follower, the latter being engaged by the 85 yoke where it is exposed by the rear aperture 48 in the box, through the springs and the front follower to the front wall of the box and through this wall by compression as in the former case to the front stops 43. 90 The box thus described acts as a means for holding the springs, spacing members, front and rear followers in assembled position, so that no single spring, spacing member or follower can be lost, and so that in case of failure of one shock-absorbing member, another, 95 assembled completely ready for operation, may be instantly substituted therefor. 100

I have thus described specifically two embodiments of my invention in order that its 105 nature and operation may be clearly understood. However, the specific terms herein are used in their descriptive rather than in their limiting sense and the scope of the invention is defined in the claims. 110

I claim—

1. In a draft gear, in combination, a horizontal yoke, a draw-bar, means connecting the draw-bar and yoke, spring plates extending through the yoke, spacing members between the springs to flex the same, and a box 115 inclosing the springs and spacing members, followers within the yoke bearing on the front and rear springs, the box having end members and openings at its front and rear ends by way of which the buffing and drawing stresses are transmitted from the yoke and draw-bar to the springs, the box being divided on a lateral plane into two sections 120 and having means for connecting the sections. 125

2. In a draft gear, in combination, a horizontal yoke, a draw-bar, means connecting the draw-bar and yoke, spring plates extending through the yoke, spacing members be- 130

tween the springs to flex the same, a box inclosing the springs and spacing members, and followers within the yoke.

3. In a draft gear having followers, a shock-absorbing member consisting of a plurality of laterally disposed plate springs, means for spacing the same and a box inclosing the springs, the box being open at each end to permit each follower to bear on the plates, and means at each end for holding the springs in place, the box being divided intermediately in a plane at right angles to the length of the draft gear.

4. A spring box for draft gear, the box being divided in a plane transverse to its length, to provide for the insertion of the springs and being open at each end and having means adjacent each opening for supporting the springs.

Signed by me at Baltimore, Maryland, 20 this 10th day of December, 1912.

THOMAS H. SYMINGTON.
